UNITED STATES PATENT OFFICE.

LEORA BOYD, OF LOS ANGELES, CALIFORNIA.

DESIGN FOR A DOLL.

51,172.

Specification for Design. Patented Aug. 21, 1917.

Application filed July 6, 1917. Serial No. 179,087. Term of patent 7 years.

To all whom it may concern:

Be it known that I, LEORA BOYD, a citizen of the United States, residing at Los Angeles, in the county of Los Angeles and State of California, have invented a new, original, and ornamental Design for Dolls, of which the following is a specification, reference being had to the accompanying drawing, forming part hereof.

In the drawing, Figure 1 is a front elevation, and Fig. 2 is a side view, each one showing my new design for dolls.

I claim:

The ornamental design for a doll, as shown.

LEORA BOYD.
